UNITED STATES PATENT OFFICE.

DANIEL NELSON, OF OAK PARK, ILLINOIS, ASSIGNOR TO MARSHALL FIELD & COMPANY, OF CHICAGO, ILLINOIS, A CORPORATION OF ILLINOIS.

METHOD OF PACKAGING MERCHANDISE AND KNOCKDOWN BOX THEREFOR.

Application filed July 13, 1925. Serial No. 43,153.

This invention relates to a procedure, as well as the instrumentalities used therein, for the packaging of merchandise to protect it from injury during carrying or shipping, and has for its object to provide a method of procedure, as well as instrumentalities, which, while enabling the packaging of goods in all respects as securely and effectively as in procedures heretofore followed, will be very much more economical as to time consumed and the cost of containers employed.

The invention proceeds upon the principle of supplying containers in the form of blanks, cut from single sheets of appropriate material, or otherwise provided in integral form but in flat condition, so that not only the manufacturer's charge for folding and assembling in container form, but the expense, inconvenience, and hazard of shipping in such form, are wholly avoided, and the box forming blanks may be supplied in larger numbers and made more conveniently accessible to the operative who uses them; also employing an assembling frame conforming in horizontal section to the section of the container to be formed from the blanks, and so arranging the hinging or folding members of the blank, or at least some of them, as to cause them to be automatically folded into position by the act of pressing the blank into the opening of the frame, thus necessitating a minimum of manipulation of side forming members, sustaining the upstanding sides of the container by the assembling frame during the packing of the goods, and using the frame, in at least some instances, to hold the cover flaps in closed position while adhesive strips or other securing means are being applied to seal the package.

In the accompanying drawings, in which the preferred details of the procedure, as well as preferred instrumentalities for performing the same, are shown by way of illustration,

Figure 1 shows in plan view and in flat or knocked down condition a blank cut and scored for convenient folding in the development of one form of container employed.

Figure 2 is a perspective view of a box assembling frame suitable for use in connection with the blank of Figure 1.

Figures 3, 4, 5, and 6 are perspective views showing, respectively, the completion

of the first, second, third, and fourth steps in the assembling, closing, and ultimate sealing of the container.

Figure 7 is a perspective view showing the container alone in the condition in which it exists in Figure 6.

Figure 8 is a plan view of an open box developed from a blank similar to that shown in Figure 1, except for slight changes in dimensions, and having added thereto an inner reinforcing wall.

Figure 9 shows a blank corresponding generally to that shown in Figure 1, but of dimensions which develop a deeper container than that developed from the blank of Figure 1.

Figure 10 is a perspective view showing an assembling frame having within it a container developed from the blank of Figure 9 and with the side walls and laps of the blank stapled to secure them in the position which they are caused to assume by the assembling frame.

Referring to Figures 1 to 7, A represents a blank cut and scored to adapt it to produce, by folding, the bottom, sides, ends, cover, and cover flaps of a box for use in packaging merchandise. B represents an assembling frame for use in forcing the folding portions of the blank into their intended relative positions, and which is of substantially less vertical dimension than that of the box to be formed. The blank A is composed of a bottom member 1, front wall 2, rear wall 3, and side walls 4 integrally united with but foldable into upstanding position from said bottom, and cover 5 hinged to the rear wall 3 and provided with closing flaps 6 and 7 which lap upon the vertical front and side walls of the body of the box in position to be secured thereto, as, for instance, by gluing strips 8 (Figures 6 and 7).

In addition to its members already enumerated, the blank A also carries lapping tabs 9 integral with the front and rear ends of the side walls 4 and folding at right angles thereto in order to permit them to lie within and provide reinforces for the overlying end portions of the front and rear walls 2 and 3.

In using the blank A and frame B just described, the blank, in flat condition, is grasped by its side walls 4 adjacent the front tabs 9 and centered over the box simul-

taneously with pressing said tabs inward, and this is followed by depressing the front portion of the blank into the frame, as suggested in Figure 3, which has the effect of closing up the front wall 2 in proper relation to the side walls and its front tabs, and immediately thereafter the rear portion of the side walls is grasped, the rear tabs 9 are pressed inward, and the rear portion of the bottom 1 is pressed into the frame, which has the effect of raising the rear wall 3 in proper position and leaving the assembled container lying open, as shown in Figure 4, and ready to receive its contents. Upon completion of the packing, the cover 5 is closed, side cover flaps 6 and end cover flap 7 are telescoped in between the frame and the walls 2 and 4 of the body of the box to retain the closure and hold the flaps snugly to the walls of the box, as shown in Figure 5, and thereupon the box and frame are inverted and the frame is slid toward the now downwardly presented top of the box, thereby exposing the free edges of the flaps 6 and 7, and gluing strips or other desirable form of securing means are applied to seal the flaps and render the package proof against tampering with.

As shown in Figure 8, a box constructed of a blank similar to the blank A, and assembled by the use of the frame B as already described, said box consisting of top 5^a with side flaps 6^a, and front flap 7^a and with front wall 2^a, rear wall 3^a, and side walls 4^a, has its front, rear, and side walls substantially reinforced by means of lining strips 10, 11 extending along the front and rear of the body of the box, bent at the corners of the box to bring their ends 10^a, 11^a into parallelism with the side walls of the box, and meeting at 12 intermediately of said sides. Such a form of reinforcement is particularly desirable when the box is of sufficient dimension and intended for goods of sufficient weight to overtax the resistance to bending of the particular weight of paper board employed, and the reinforcing liner is particularly effective in sustaining the box against crushing stresses imposed vertically thereon, for instance, by arranging a number of completed boxes in a pile. Preferably, the reinforcing lining strips are stapled, as suggested at 13, to the members of the box proper over which they lap, and because of the use of these staples, the corner tabs 9^a are hinged to the front and rear walls rather than to the side walls, as in Figures 1, 3, and 4. It is to be understood, however, that the reinforcing liner 10, 11 can be used just as well in the box shown in Figure 4 as in that shown in Figure 8, such liner to be secured by staples 13 or other equivalent means wherever used.

As shown in Figures 9 and 10, the invention may be applied to boxes of such depth

as to render unavailable the method of holding the sides in assembled relation and sealing the cover by gluing strips passing over the cover flaps to the bottom of the box. In this instance, the reinforcing tabs will 70 preferably be of greater horizontal dimension, and in the finished box each vertical wall will carry one tab so that the walls will all be reinforced alike. Thus, the blank C, shown in Figure 9, comprises the bottom 75 1^c, front wall 2^c, rear wall 3^c, and the two end walls 4^c, to each of which is hinged one of the reinforcing tabs 9^c while the cover 5^c, with its closing flaps 6^c, 7^c, will be hinged to the rear wall 3^c as already described. In 80 making a box from the blank C, an assembling frame D of substantially less vertical dimension than that of the box to be formed, will be employed, and the blank will be gathered in the frame very much as described in 85 connection with Figures 1 to 6, except that the members which carry the lapping tabs, for instance, the right-hand side wall 4^c carrying the tab 9^c and the front wall 2^c with its tab 9^c, will be grasped first and used 90 to force the blank down into the frame as their tabs 9^c are deflected, and then the rear wall 3^c with its tab 9^c and the left-hand side wall 4^c with its tab 9^c, will be grasped in 95 completing introduction of the blank into the frame and completing assembly of the box. In order that the cover 5^c, with its flaps 6^c, 7^c, may be secured after removal of the box from the frame, if it should be desired to do so, the sides 2^c, 4^c are stapled to the reinforcing tabs 9^c, as suggested at 14, except where the tabs 9^c, carried by the left-hand side wall 4^c, laps over the rear wall 3^c and is accessible to the stapling machine only 100 with difficulty, and to take the place of a 105 staple in that situation the blank is formed with a special tab 9^a at the upper margin of the rear wall 3^c, which is of reduced dimension so that it can be cut out of the tab 9^c on the left-hand side wall 4^c; and this supplemental tab is lapped on the outside of the left-hand end wall 4^c and receives the staple 110 14^c, as clearly shown in Figure 10.

A box constructed of the blank C and assembled as described with reference to Figure 10, can have its cover and closing flaps secured by gluing strips, as shown in Figures 6 and 7, or by means of a cord or other flexible tying means, as may be desired.

I claim:

1. The improvement in the art of packaging merchandise, which consists in taking a box forming blank having bottom, top, and wall forming members constructed for folding upon prearranged lines determinate of the horizontal dimensions of the box, introducing such blank into a frame with the walls of the box sustained by said frame in upstanding position, the frame being of less vertical dimension than the box, and then 125

packing the merchandise in the box while so sustained.

2. The improvement in the art of packaging goods, which consists in taking a box forming blank in flat form and consisting of a bottom member carrying walls forming members and a cover member carrying closing flap members, said members being hinged together on prearranged lines which are definitive of the size of the box to be formed, forcing the bottom of the box into an assembling frame corresponding to the box in horizontal dimensions but of less vertical dimension than the box, packing the merchandise in the box, closing the cover and introducing the cover flaps between the frame and the box, sliding the frame on the box to expose the free ends of the cover flaps, and then securing said flaps and releasing the box from the frame.

3. The improvement in the art of pack-

aging merchandise, which consists in taking a flat box blank consisting of a bottom and cover members having wall and flap forming members united therewith on predetermined folding lines definitive of the dimensions of the box, the vertical dimension of the cover flaps being approximately that of the wall forming members, placing said blank over an assembling frame and forcing it thereinto to cause the wall forming members to assume upstanding position, packing the box, closing the cover, introducing the flaps between the box and the frame, inverting the closed box and frame, sliding the frame away from the bottom of the box to expose the free ends of the flaps, and sealing said flaps to the box.

Signed at Chicago, Illinois, this 2nd day of July, 1925.

DANIEL NELSON.
